(57) **CLAIM**

The ornamental design for a replaceable cleaning cloth for robotic cleaner, as shown and described.

DESCRIPTION

The patent or application file contains at least one drawing executed in color. Copies of this patent or patent application publication with color drawing(s) will be provided by the Office upon request and payment of the necessary fee.

1. Replaceable cleaning cloth for robotic cleaner
2. Replaceable cleaning cloth for robotic cleaner

1.1 : Front

1.2 : Back

1.3 : reference

1.4 : reference

1.5 : reference

2.1 : Front

2.2 : Back

2.3 : Enlarged

2.4 : Enlarged

Fig.1.1 is a front view of a first design of a replaceable cleaning cloth for robotic cleaner; Fig.1.2 is a rear view thereof; Figs.1.3-1.5 are reference views in applied state thereof; Fig.2.1 is a front view of a second design of a replaceable cleaning cloth for robotic cleaner; Fig.2.2 is a rear view thereof; Fig.2.3 is an enlarged view of the portion

(Continued)

A in FIG. 2.1; and Fig. 2.4 is an enlarged view of the portion B in FIG. 2.2; the product is attached to a bottom surface of a replaceable cleaning cloth for robotic cleaner; reproductions 1.3, 1.4 and 1.5 is for reference purposes only and forms no part of the claimed design.
